CLAIM

I claim the ornamental design for a bowl, as shown and described.

DESCRIPTION

FIG. 1 is a top perspective view of a bowl showing my new design;

FIG. 2 is a top plan view thereof;

FIG. 3 is a front elevation thereof, the rear being a mirror image thereof;

FIG. 4 is a left side elevation thereof;

FIG. 5 is a right side elevation view thereof;

FIG. 6 is a bottom plan view thereof; and,

FIG. 7 is a cross-section thereof taken along line 7—7 in FIG. 2.
